UNITED STATES PATENT OFFICE.

JOHN W. BAIRD, OF CHICAGO, ILLINOIS.

SPARK-PLUG.

1,190,846.

Specification of Letters Patent.

Patented July 11, 1916.

Continuation in part of application Serial No. 57,460, filed October 23, 1915. This application filed January 24, 1916. Serial No. 73,982.

To all whom it may concern:

Be it known that I, JOHN W. BAIRD, a citizen of the United States, and a resident of the city of Chicago, county of Cook, and State of Illinois, have invented certain new and useful Improvements in Spark-Plugs, of which the following is a specification.

My invention relates to improvements in spark plugs, the present application being in part a division of my pending application Serial No. 57,460, filed October 23rd, 1915, for spark plugs.

The object of this invention is the production of a spark plug which will be so constructed as to practically eliminate the possibility of fouling when the plug is in use.

A further object is the production of a spark plug which may be economically manufactured and which will be highly efficient in operation.

The invention consists in the combinations and arrangements of parts hereinafter described and claimed.

The invention will be best understood by reference to the accompanying drawing forming a part of this specification, and in which—

Figure 1 is a central longitudinal section of a spark plug embodying the invention, Fig. 2 is a bottom plan view thereof, Fig. 3 is a central longitudinal section through the lower portion of a spark plug of a slightly modified form, and Fig. 4 is a bottom plan view of Fig. 3.

The form of the construction as illustrated in Figs. 1 and 2 comprises a spark plug consisting of an outer tubular body 1 which forms one pole of the plug and an inner slender rod 2 which is arranged centrally in the member 1 and which forms the other pole of the plug. The parts 1 and 2 are connected together and insulated from each other in the usual manner.

Provided at the lower end of the inner pole member 2 is an elongated bar 3 secured to the member 2 by means of a transversely extending pin 4 so as to permit of rocking movement of said bar. The pin 4 passes through ears 5 which project upwardly from the longitudinal edges of bar 3 midway the ends of the latter. Opposite sides of member 2 are flattened as seen to accommodate the ears 5. The member 3 is thus permitted free rocking movement within a fixed range, the movement thus afforded being deter-

mined by the corners 6 at the lower end of the pole member 2 which are adapted for engagement against the upper side of bar 3 in order to permit rocking movement thereof, as shown in dotted lines in Fig. 1. The arrangement is such that the bar 3 will be prevented from contacting with the pole member 1 of the spark plug a gap being always formed between the ends of said bar and the lower or inner edge of the member 1 for the jumping of the spark.

With this construction it will be seen that during explosion in the engine cylinder or upon rushing of the gases from the cylinder during scavenging of the latter the disturbance in the cylinder will have the effect of vibrating the member 3 so as to shake any soot, carbon, or other foreign matter therefrom in order to prevent fouling in the operation of the spark plug.

In the form shown in Figs. 3 and 4 the lower end of the pole member 2 projects through a slot 7 provided in the oscillatory member 3 so that the ends of said slot constitute stops adapted for engagement against the opposite sides of said pole member in limiting the amplitude of oscillation of the member 3' as will be readily understood. Also in this form one end of the member 3' is reduced in width, thereby unbalancing said member, and whereby the opposite end of the same will normally be in lowered position, as shown in Fig. 3, because of gravity. The reduction of one end of said member 3' also reduces the area of the under side thereof so that in the operation of the engine in which the plug is employed, the opposite end of said member 3' will be unevenly affected by the pressure in the cylinder or the rapidly moving gases passing the spark plug, with the result of insuring the desired vibration of said member 3'. The difference in weight of the opposite ends of the bar also aids in obtaining this result inasmuch as the heavier or larger end of the member 3' will be elevated by the pressure of the gases in the cylinder and lowered by gravity.

While I have illustrated and described the preferred forms of construction for carrying my invention into effect, these are capable of variation and modification without departing from the spirit of the invention. I therefore, do not wish to be limited to the precise details of construction set forth, but desire to avail myself of such variations and modi-

fications as come within the scope of the appended claims.

Having described my invention what I claim as new and desire to secure by Letters 5 Patent is:

1. A spark plug for explosion engines comprising two poles; a member rockingly mounted intermediate its ends upon one of said poles so that in the oscillation of said 10 member the ends thereof will move toward and from the other pole, one end of said member being heavier than the other; and means for limiting oscillatory movement of said member to prevent contact thereof with 15 said last mentioned pole, substantially as described.
2. A spark plug for explosion engines comprising two poles; a member rockingly mounted intermediate its ends upon one of 20 said poles so that in the oscillation of said member, the ends thereof will move toward and from the other pole, the under side of one end of said member disposed parallel with the axis of said member being of less 25 area than that of the corresponding side of the other end; and means for limiting oscillatory movement of said member to prevent contact thereof with said last mentioned pole, substantially as described.
3. A spark plug for explosion engines comprising an outer tubular body forming one pole of the plug; an inner centrally positioned longitudinally extending member arranged in said body and forming the other 30 pole of the plug; a transversely extending elongated member mounted intermediate its 35 ends upon the inner end of said last mentioned member for free vertical movement about a transverse axis whereby, in the oscillation of said member, the ends thereof will 40 move toward and from opposite sides of said tubular member; and means for limiting oscillatory movement of said elongated mem-

ber to prevent contact thereof with the tubular member, substantially as described.

4. A spark plug for explosion engines comprising an outer tubular body forming one pole of the plug; an inner centrally positioned longitudinally extending member arranged in said body and forming the other 50 pole of the plug; a transversely extending elongated member mounted intermediate its ends upon the inner end of said last mentioned member for free vertical movement about a transverse axis, the under side of 55 one end of said member disposed parallel with the axis of said member being of less area than that of the corresponding side of the other end; and means for limiting oscillatory movement of said member to prevent contact thereof with the tubular pole member, substantially as described. 60

5. A spark plug for explosion engines comprising an outer tubular body forming one pole of the plug; an inner centrally positioned longitudinally extending member arranged in said body and forming the other pole of the plug; a transversely extending bar mounted centrally upon the inner end of 65 said member for free oscillatory movement about a transverse axis; and shoulders at the inner end of said central member adapted for engagement with the upper side of said bar at opposite sides of the pivot thereof for limiting oscillatory movement of said 70 bar to prevent contact thereof with said tubular pole member, substantially as described. 75

In testimony whereof I have signed my name to this specification in the presence of 80 two subscribing witnesses.

JOHN W. BAIRD.
